TABLE REVERSING MECHANISM FOR
GRINDING MACHINESStephen E. Woodbury, Beverly, Mass., assignor to
Reid Brothers Company, Inc., Beverly, Mass., a
corporation of Massachusetts

Application November 23, 1945, Serial No. 630,242

8 Claims. (Cl. 51—92)

1

This invention relates to grinding machines and comprises improvements in the table reversing mechanism of such machines. The general objects of the invention are to provide reversing mechanism which shall be simple, compact, reliable in operation, convenient in use, readily adjustable to vary both the path and location of the travel of the work table, and completely guarded so that there is no danger of the operator being caught by moving parts.

Heretofore it has been the practice to provide the work table of grinding machines with a pair of adjustable reversing dogs movable with the table and acting to trip reversing mechanism. Trouble has often been occasioned with the prior construction by the unnoticed loosening of one of the reversing dogs which are subjected to the shock of reversal and thus tend to work loose. The operator, moreover, in moments of inattention is likely to have his hand caught by the moving dogs. These dangers are obviated and important advantages achieved by the mechanism of my invention which is characterized by a longitudinal rock shaft mounted in front of the work table in completely guarded condition, and carrying a pair of longitudinally adjustable cams thereon which cooperate with a cam oscillating element, such as a cam roller carried by the work table. The rock shaft is connected to reversing mechanism. Accordingly, whenever the rock shaft is oscillated by contact of the cam roll with either of the adjustable cams, the reversing mechanism is moved from one position to the other and the path of the table correspondingly terminated and its travel reversed. Other features of the invention relate to the shape and adjustment of the cams, to provision for simultaneously adjusting them, and to means for guarding all moving parts of the mechanism.

These and other features of the invention will be best understood and appreciated from the following description of a preferred embodiment thereof, selected for purposes of illustration and shown in the accompanying drawings, in which:

Fig. 1 is a view in perspective of so much of a grinding machine as is necessary to understand the invention.

Figs. 2, 3 and 4 are fragmentary views of different parts of the mechanism.

The invention is herein shown as embodied in a grinding machine of well-known commercial type including a main frame 10 and an upright column 11 in which is mounted a motor-driven grinding wheel 12. Laterally extending ways are formed in the frame 10 for a cross slide 13 which is arranged to be adjusted transversely either by

2

hand or automatically in the operation of the machine. The mechanism for adjusting the cross slide is not herein shown since it forms no part of the present invention but is well known to those familiar with the industry.

6 A work table 14 is mounted for longitudinal reciprocation on the cross slide 13 and is herein shown as equipped with a magnetic chuck 15 on which the work may be clamped for travel beneath the grinding wheel 12. The work table is herein shown as provided in its front face with an undercut T-shaped longitudinal groove 16, and in this groove is adjustably mounted a block 17 carrying an outwardly projecting cam roll 18. 10 It is not ordinarily necessary to adjust the position of the cam roll 18 in the table 12 after the machine has once been set up, but the illustrated provision for adjustment is a matter of convenience for that purpose.

15 Attached to the cross slide 13 and adjacent to the front face of the table is a pair of spaced brackets 19 and 20 in which is journaled a rock shaft 21. The shaft 21 is splined throughout its length and carries a pair of double wedge cams 23 and 24 which are keyed to the shaft for longitudinal adjustment and cooperate with the cam roll 18 in rocking the shaft in opposite directions. To this end the two cams are disposed with their operative faces inclined in opposite directions, that is to say, the point of the cam 23 is directed 20 upwardly and the point of the cam 24 is directed downwardly. At its right-hand end the shaft 21 is provided with a crank arm 25 and this, in turn, is connected through a vertical link 26 to an arm 27 on the outer end of a shaft 28 forming a part 25 of a reversing switch enclosed in the casing 29 secured to the machine frame. The details of the reversing switch are not herein shown since it is a well-known piece of commercial equipment. It is sufficient to say that the reversing switch is 30 included in the circuit of an individual motor which drives the work table first in one direction and then in the other. When the shaft 21 is rocked, the reversing switch is thrown from one 35 position to the other, thus terminating the travel of the table in one direction and starting it back in the reverse direction. The construction and arrangement of the reversing motor and switch are disclosed in my prior application Ser. No. 609,522, filed August 8, 1945.

40 The brackets 19 and 20 carry a horizontal cover plate 30 which encloses the shaft 21 and the mechanism carried thereby. A vertically disposed front plate 31 completes the enclosure and completely safeguards the moving parts of the reversing mechanism. The front plate 31 is 45 50 55

slidably mounted on supporting blocks 32 and 33 which project forwardly from the brackets 19 and 20. The shaft 21 is retained against longitudinal movement by a collar 34 fast to its left-hand end as shown in Fig. 3, and a collar 35 fast to its right-hand end between the bracket 20 and the crank arm 25. The crank arm 25 and its associated mechanism are enclosed in a rectangular casing 36 secured to the right-hand side of the cross slide 13. The front plate 31 is mounted for horizontal adjustment upon the supporting blocks 32 and 33, and for this purpose is provided at its left-hand end with an adjusting screw having a knurled head 37 and being threaded into the bracket 19. When this screw is turned, the plate 31 is shifted longitudinally in one direction or the other, and to permit this adjusting movement a guide slot is provided in the casing 36.

It has been explained that the cams 23 and 24 are splined to the rock shaft 21. The position of these cams may be individually adjusted and set by flanged slides 38 and 40 in cooperation with the slotted front plate 31. Each of the cams is provided with a circumferential slot in its hub. In the slot of the cam 24 is received the flange of the slide 38, and in the slot of the cam 23 is received the flange of the slide 40. The slide 38 is provided with a screw having a knurled clamping nut 39, and the slide 40 is provided with a screw having a knurled clamping nut 41. The screws project forwardly from their respective slides and carry washers sliding in the slot of the front plate 31. A guide stud projects outwardly from each flanged slide 38 and 40 adjacent to its screw. The longitudinal slot in the front plate 31 therefore forms a guideway permitting free longitudinal movement of the flanged slides while preventing angular displacement thereof. It will be understood that either slide may be clamped in any selected position of adjustment by screwing in its clamping nut against the front plate.

From the foregoing description it will be understood that the clamping screws 39 and 41 may be loosened, and the cams 23 and 24 independently adjusted to the desired limiting positions of the stroke of the work table. They are then clamped in stationary position and the machine will operate with the work table moving in a predetermined path and automatically reversing at each end thereof. Either or both clamping screws may be loosened and reset conveniently to shift the location of the path or its point of reversal at either end. By bodily adjusting the front plate 31 through the medium of the adjusting screw 37, the reversing cams 23 and 24 are longitudinally and simultaneously adjusted, thus shifting the location of the path of the work table while maintaining it constant in extent. In facing the machine the operator has before him only three stationary clamping or adjusting devices, and these may be conveniently adjusted either while the machine is at rest or while it is in operation and without any possibility of contact with any moving part of the machine.

The reversing cams 23 and 24 are made double wedge in shape for two reasons: in the first place their symmetrical construction permits them to be used in either of the positions required on the shaft 21. They are simply arranged thereon in opposing positions. In the second place, should the cam roll 34 be allowed to pass outside the space between the cams, and the cam shaft be turned in the meantime, then the outside wedge face of either cam would serve to turn the shaft back into position. There is, of course, no such

safety provision as this in reversing dog mechanisms heretofore known. The axis of the cam roll 34 is located at the same level as the axis of the cam shaft 21.

5 While the reversing mechanism of my invention is shown as embodied in a grinding machine it may be usefully applied to other machine tools having a cutting tool in combination with a reciprocatory table.

10 Having thus disclosed my invention and described in detail an illustrative embodiment thereof, I claim as new and desire to secure by Letters Patent:

15 1. A grinding machine having a grinding wheel and a reciprocatory table carrying a projecting cam roll, a rock shaft disposed parallel to the path of said table, a pair of cams with oppositely inclined operating faces adjustably mounted on said shaft with the said cam roll located between them, and a reversing switch for the table connected to and operated by said rock shaft.

20 2. In a grinding machine equipped with a grinding wheel, a cross slide and a reciprocatory work table thereon, a rock shaft mounted in the cross slide adjacent to the path of the table, a pair of cams splined to said shaft and longitudinally adjustable thereon, a cam roll carried by the table and movable into operative engagement with one of said cams after the other, and a reversing switch connected to the shaft.

25 3. A grinding machine equipped with a grinding wheel, a cross slide and a work table mounted to reciprocate thereon in a path adjacent to the wheel, the said table having a longitudinally adjustable cam roll projecting from one of its faces, a rock shaft journaled in the cross slide, spaced cams on said shaft located in the path of said cam roll and on opposite sides thereof, and a reversing switch connected to said rock shaft.

30 4. In a grinding machine equipped with a grinding wheel, a cross slide and a work table mounted to reciprocate thereon in a path adjacent to the wheel, the said table having an adjustably mounted cam roll projecting from its front face, a rock shaft mounted on the cross slide adjacent to the front face of the table, a pair of cams splined to the shaft on opposite sides of the said cam roll, means for adjustably clamping said cams in any selected positions on said shaft, means for simultaneously adjusting both cams together, and a reversing switch operatively connected to the said shaft.

35 5. In a grinding machine or the like, a reciprocatory table carrying a forwardly projecting cam roll, a stationary shaft disposed longitudinally in front of the said table with its axis at substantially the same level as the axis of the cam roll, a pair of double wedge cams splined to said shaft, a flanged slide connected to each cam, clamping means carried by each slide, and a reversing switch operated by oscillation of said shaft.

40 6. In a grinding machine or the like, a reciprocatory table, a stationary guard plate located in front of the table, a longitudinal rock-shaft journaled between the table and guard plate, reversing mechanism operated by the rock-shaft, a cam oscillating element carried by the table and movable in a path adjacent to the rock-shaft, spaced cams splined to the rock-shaft and arranged to cooperate with said oscillating element, and normally stationary clamping devices associated with the guard plate for adjustably determining the setting of said cams.

45 7. In a grinding machine or the like, a re-

reciprocating table carrying a projecting cam roll, a stationary guard plate located in front of the table and spaced therefrom to permit free movement of the cam roll with the table, a longitudinal rock-shaft journaled between the table and the guard plate, a reversing mechanism for the table connected to the rock-shaft, a pair of double wedge cams splined to said shaft on opposite sides of the cam roll, normally stationary clamping devices associated with the guard plate and being connected to the cam rolls to hold them independently in longitudinally adjusted position upon the rock-shaft and at the same time permitting oscillatory movement thereof with said shaft, and means for longitudinally adjusting the guard plate together with said clamping devices and the said cams.

8. A grinding machine equipped with a grinding wheel, a cross slide and a work table mounted to reciprocate thereon in a path adjacent to the grinding wheel, supporting members fastened to

the cross slide in front of the work table, a rock shaft journaled in said supporting members to rock about an axis parallel to the path of the reciprocating work table, cooperating means on the work table and shaft for rocking the shaft in opposite directions at predetermined points in the travel of the table, and a reversing switch operatively connected to said shaft.
